(57) **CLAIM**

The ornamental design for an optical disk container, as shown and described.

DESCRIPTION

FIG. 1 is a front, top, left perspective view of an optical disk container showing my design;

FIG. 2 is a front elevational view thereof;

FIG. 3 is rear elevational view thereof;

FIG. 4 is a left elevational view thereof;

FIG. 5 is a right elevational view thereof;

FIG. 6 is a top plan view thereof;

FIG. 7 is a bottom plan view thereof; and,

FIG. 8 is a perspective view illustrating use of the optical disk container in FIG. 1, wherein a lid allowing storage/removal of optical disks is in an opened position.
